8 Claims. (Cl. 233—20)

The present invention relates to improvements in centrifugal separators to separate sludge from liquids, and the separator is of the type having a centrifugal bowl provided with a rotatable spindle and separating chambers and comprising two parts displaceable in the axial direction relative to each other, of which parts one constitutes a closing and opening member which through the intermediary of an actuating liquid conducted through the centrifugal bowl and influenced by the centrifugal force can be displaced for the closing and opening of one or several peripheral sludge discharge openings for intermittent discharge of suspended sludge collected within the bowl.

The term "sludge" as used herein is to be considered as designating not only impurities in liquids, but any material including a large proportion of solids of higher specific gravity than the liquids in which they are suspended.

In sludge separators of this type it is known to provide the separator with means, such as valves through which the actuating liquid can quickly be discharged from the centrifugal bowl in order thereby to obtain a so quick opening of the sludge discharge openings that the separated sludge or the separated solid material can be instantaneously discharged from the centrifugal bowl. By such an instantaneous discharge of the sludge or the solid material, which may e.g. be sticky, the less concentrated sludge will carry the more concentrated sludge deposited on or sticking to the bowl wall, along out through the sludge discharge openings so that there will not be any one-sided deposit of sludge on the bowl wall which may cause undesired shakings of the centrifugal bowl. If on the other hand it is only a question of separating such matters as contain nothing but plastic sludge, e. g. organo-therapeutic matters, such as Heparin or similar plastic substances, fruit pulp and substances corresponding thereto, which can only be concentrated to a minor degree and frequently do not give any firm deposit on the bowl wall, it will be advantageous, under continuous feeding of separating material to the centrifugal bowl, intermittently and partially to be able to discharge the most concentrated sludge lying nearest the periphery wall of the bowl without allowing the less concentrated sludge or cleaned liquid lying nearer the axis of rotation to escape, seeing that only the most concentrated sludge is allowed to be discharged from the centrifugal bowl. In such a discharge of sludge from the centrifugal bowl it is not possible to use a complete opening of the sludge discharge openings which is normally established by evacuating the actuating liquid from the centrifugal bowl through an actuating valve thus obtaining, on account of the great hydrostatic pressure produced by the centrifugal force in the separating bowl as well as in chambers containing the actuating liquid, an instantaneous and complete opening of the sludge discharge openings. The said hydrostatic pressure may in a centrifugal separator of the type referred to be 50 atm. or more, which pressures are released in the course of a time interval which is less than

2

a second, and so the controlling or regulating means for the regulation of the feeding of the actuating liquid must be exceedingly sensitive.

An important feature of the invention consists of the arrangement of the separator in such a manner that at predetermined time intervals during the operation, the most concentrated sludge present nearest the inner circumference wall of the centrifugal separator is discharged during the separation, while the remaining part of the sludge-containing mixture is retained for a continued separation and concentration of the sludge.

Another feature of the present invention is to arrange the separator in such a manner that it is possible at predetermined time intervals to obtain a controlled partial opening of the sludge discharge openings of the centrifugal bowl and at longer time intervals a complete opening of the sludge discharge openings of the centrifugal bowl.

Still another feature of the invention is to arrange the centrifugal separator in such a manner that it is possible to obtain such a relation between the quantity of the actuating liquid continuously oozing out from the centrifugal bowl for the actuation of the closing member for the sludge discharge openings of the centrifugal bowl and the amount of the actuating liquid which is fed to the centrifugal bowl that the pressure of the actuating liquid will cause said closing member 15 to be balanced during an intermittent partial opening of the sludge discharge openings.

Still another feature of the invention is to arrange the centrifugal separator in such a manner that the length of the time intervals between the sludge discharges are determined automatically by means of a timer, while the length of the time intervals during which the sludge discharges take place is determined by means of the energy contained in the sludge being discharged, either through current impulses in the driving electric motor of the centrifugal separator or through the influence of the sludge on mechanical means.

Further features of the invention will be apparent from the following specification in connection with the accompanying drawing.

The invention as illustrated in the drawing shows a manner of construction of the centrifugal separator according to the invention, in which

Fig. 1 shows a partial section through the centrifugal bowl along its axis of rotation and regulating members of the centrifugal separator,

Figs. 2, 3 and 4 details on a somewhat larger scale and in section along the longitudinal axis, and

Fig. 5 another manner of construction of the regulating members.

The centrifugal separator has a centrifugal bowl comprising an upper part 1 and a lower part 2, 2a, which are held together by means of a threaded ring 3, the parts 2, 2a being arranged on a rotatable spindle 4. The separation material is fed through an inlet pipe 5 to the middle tube 5a of the centrifugal bowl and from there through channels 6 to the separating chamber 7. The separating chamber is provided with a suitable stack of discs 8 and accelerating wings 9. Furthermore the centrifugal bowl has sludge discharge openings 10 for a lighter liquid component and discharge openings 11 for a heavier liquid component and peripheral discharge openings 12 for the separated sludge or solid material. From the said discharge openings 12 the separated sludge or solid material is impelled into a stationary chamber 13 arranged around the centrifugal bowl through an annular slot 14 arranged in the wall of the said chamber. The discharge openings 12 may be closed and opened by means of an annular piston 15 which is axially displaceable in an incision in the bowl part 2, 2a, and can be moved towards and away from a

gasket 16 arranged in the bowl part 1. The piston 15 is kept against the gasket 16 by means of an actuating liquid influenced by the centrifugal force. The closing liquid is introduced into a chamber 17 constructed in the bowl part 2, 2a, beneath the piston 15. The closing liquid is under pressure conducted through a tube 18 to an annular channel 19 formed in the bowl part 2, 2a and is from there, under the influence of the centrifugal force, impelled through a channel 20 to the chamber 17. Normally through the intermediary of the intermittent opening of the sludge discharge openings 12, the actuating liquid will be conducted to the outer surroundings or exterior of the centrifugal bowl through a discharge arrangement that includes an actuating valve 21 mounted in the bowl wall and counter balanced by means of a piston 22 arranged in a chamber 23 formed in the bowl part 2, 2a and connected to the valve cone of the valve 21 by means of a rod 24 passing through an incision 25 in the bowl part 2, 2a.

When treating certain sludge containing materials, the sludge separated in the separating chamber 7 is intermittently discharged through the discharge openings 12, the supply of the material through the pipe 5 and the supply of actuating liquid through the tube 18 being stopped, and there is thereafter introduced under pressure an actuating liquid through a tube 26 to an annular channel 27 formed in the bowl part 2, 2a and from there it is under the influence of the centrifugal force flung through a channel 28 to an incision 23 behind the piston 22 which is thereby caused to be moved outwardly opening the valve 21. In this manner the actuating liquid is discharged from the chamber 17, and so the hydrostatic pressure in the separating chamber 7 and in a chamber 29 above an annular flange 30 on the piston 15 quickly moves the piston 15 downwards opening the sludge discharge openings 12. By such a swift and complete opening of the openings 12 all the sludge and the separating material are discharged from the separating chamber. When the supply of actuating liquid for the chamber 23 is stopped, the actuating liquid present in this chamber is ejected through the piston 22 and on through the opening 31 in the wall of the bowl part 2, 2a. When thereafter actuating or closing liquid is conducted to the chamber 17, the piston 15 is displaced towards the gasket 16 and closes the openings 12, whereafter material to be separated may again be fed to the separating chamber 7.

In the treatment of sludge-containing separating material including plastic sludge which can only be concentrated to a minor degree, it is advantageous to be able to discharge intermittently only the most concentrated sludge present in the separating chamber adjacent its periphery without stopping the supply of the separating material to the separating chamber. For this purpose is required a slow and only partial opening of the sludge discharge openings 12. To achieve this object the centrifugal separator has a constantly open oozing opening for the actuating liquid, which opening has a flow area not so great that it is impossible during a continuous supply of actuating liquid, to maintain the necessary hydrostatic pressure in the chamber 17 against the piston 15 to keep the sludge discharge openings 12 closed, but through a suitable regulation of the supply of the actuating liquid the hydrostatic pressure reduced so much that the sludge discharge openings 12 are opened slowly and partially. Such regulation of the supply of the actuating liquid must be made at time intervals adjusted according to the quantity of sludge desired discharged at each opening of the openings 12. It is preferable that the regulation of the actuating liquid is performed automatically within the said time intervals, the latter being determined according to the nature and quantity of the sludge to be discharged. For this purpose is arranged a timer 32 which is adapted within the said time intervals to break an electric current. This timer may for instance be composed by a timer 32a, which may be set to operate

within a time interval of a few minutes, and a timer 32b, which can be set to operate within a time interval of a few seconds, thus the timer may be adjusted very exactly according to the desired times for the sludge discharges. The timer receives its current from a couple of current-carrying wires 33 and 34, and it is provided with a contactor 35 which through suitable connections can close a circuit through an electro magnet 36. This magnet is capable of attracting an armature 37 on a regulating valve 38 which is inserted in the supply pipe 18, and which in accordance with its setting can regulate the supply of actuating liquid to the chamber 17. When the timer 32 breaks the circuit through the magnet 36, the magnet will release the armature 37, and the valve 38 will now adjust itself in the manner that the pressure on the piston 15 is reduced so much that the sludge discharge openings 12 are opened partially. When the sludge oozes out into the openings 12 and consequently gets at a bigger distance from the axis of rotation of the centrifugal bowl, an increased energy is required for keeping the bowl at its normal speed, or the bowl will be braked in such a manner that its speed will be reduced. Included in the circuit of the magnet 36 is a contactor 39 which through wires 40 receives current from the electric motor that drives the bowl. As above mentioned when sludge is flung outwardly from the bowl through the openings 12, the sludge will be discharged on an increased radius, which means that the motor will be braked a little, that is, its rate of revolution is somewhat decreased. To enable the motor, after the sludge discharge, to again reach its normal rate of revolutions, it consumes for a moment an increased strength of current; and it is this current impulse that is used to influence the contactor 39. When this contactor is thus operated to close the magnet circuit and attract the armature 37, the valve 38 will again be adjusted to conduct the normal amount of actuating liquid to the chamber 17, whereby the pressure on the piston 15 is increased so that the latter will again close the sludge discharge openings 12. Instead of using reoccurring electric impulses from the driving motor for the closing of the circuit through the magnet 36, it is possible to use the energy in the sludge being discharged. For this purpose it is possible, as shown in Fig. 5, to arrange in the wall of the annular chamber 13 opposite the discharge openings 12 a membrane or movable member 41 in connection with a contactor 42 which is inserted in the circuit of the magnet 36, and which closes the said circuit when the sludge, which is being discharged, hits the member 41.

In the described example is used a valve 38 which closes by currentless solenoid coil. If a corresponding valve is used closing by current-carrying coil, the function of the contactors will be reversed, and the principle of the invention thus remains unchanged.

The oozing opening for the oozing out of the actuating liquid may by way of example be performed as illustrated in Figs. 2, 3 or 4. An oozing channel 49 is carried through the cone of the valve 21 as in Fig. 4; or the rod 24, connecting the valve cone of the valve 21 with the piston 22, has a central bore 43 which passes freely through the valve 21, and which by means of an oozing channel 44 is connected with the chamber 17 as in Figs. 1 and 2. The oozing channel 44 is situated at such a distance from the axis of rotation that the pressure from the actuating liquid against the piston 15 can only be decreased to such a degree, in relation to the opposed pressure, that the pressure will balance the piston 15 in a position for partial opening of the sludge discharge openings 12.

To limit the amount of the actuating liquid which is subjected to a comparatively great pressure, the oozing channel has a comparatively small cross sectional area, and to safeguard against the possibility of collection in the channel of solid particles which may be present in the actuating liquid, the oozing channel may by way of example be constructed in such a manner that the channel has a decline towards the axis of rotation, that is to

say, the channel extends at an angle to a radial line radiating from the axis of rotation of the bowl. Furthermore the outlet end of the opening lies nearer the axis of rotation than is the case with its inlet opening and hence by a quick and complete discharge from the chamber 17 through the valve 21 the actuating liquid will carry such solid particles away. Instead of arranging the oozing channel 44 in the valve rod 24, it can be arranged in the lower part 2 of the bowl itself as shown in Fig. 3 where the oozing channel is designated by 48. Furthermore the cross sectional area of the oozing channel may be varied for oozing out of predetermined amounts of actuating liquid per time unit by the use of interchangeable parts or elements such as 45 in Fig. 3, removably insertable in the channel, the oozing channels or passages of which elements having different predetermined cross sectional areas. In such a construction of the oozing channel the outlet openings of the said parts open into a liquid reservoir 46 which has a greater cross sectional area than the cross sectional area of the oozing channels, and thus during the discharge of the sludge there will always be so much liquid 47 in the reservoir that the liquid covers the openings of the oozing channel and thus prevents solid particles from depositing in the oozing channel. In case of complete discharge of sludge and separating material from the separating chamber the liquid 47 will be carried along by the actuating liquid discharged from the chamber 17.

I declare that what I claim is:

1. In a centrifugal separator, the combination of a centrifugal bowl mounted for rotation on a vertical axis to effect continuous discharge of liquid effluents and provided with peripheral sludge discharge openings for suspended solid material collected within the bowl, a sealing piston for controlling the sludge discharge through said openings and mounted for axial reciprocation within the bowl, said piston being actuated to intermittent displacement partly by pressure of the treated liquid and partly by means of an actuating liquid influenced by centrifugal force, conducting means to conduct the actuating liquid to two annular grooves in the bottom of the bowl and conducting means to conduct the actuating liquid from one of the said annular grooves to a space below said piston, said space being connected with a discharge arrangement for the actuating liquid, this discharge arrangement comprising a valve means and hydrostatic means for displacement of said valve means to an open position to permit the discharge of the actuating liquid and the simultaneously resulting movement of said piston to its complete open position for sludge discharge, means to permit the actuating liquid constantly to ooze out from the said space, automatic means controlled by the energy contained in the sludge for regulating the flow rate of actuating liquid conducted to the said annular groove in relation to the rate of actuating liquid oozing out from the said space to the effect of displacing said piston to a position for a partial opening of the sludge discharge openings in the bowl and simultaneous partial sludge discharge, said automatic means holding the piston balanced in its partially open position without stopping the supply to the bowl of the material to be separated, and timer means associated with said automatic means for controlling the length of the partial openings and the intervals between such.

2. In the structure of a centrifugal separator as claimed in claim 1 in which said valve means includes a valve and said means to permit the actuating liquid constantly to ooze out from said space is a channel formed in said valve.

3. In the structure of a centrifugal separator as claimed in claim 1 in which said means to permit the actuating liquid constantly to ooze out from said space is a channel formed in the bottom of the bowl and in communication with said space below the piston, said channel extending at an angle to a radial line radiating from the

axis of rotation, and a replaceable element in said channel with an oozing opening of predetermined cross sectional area.

4. In a centrifugal separator, the combination of a centrifugal bowl mounted for rotation on a vertical axis to effect continuous discharge of liquid effluents and provided with peripheral sludge discharge openings for suspended solid material collected within the bowl, an annular sealing piston for controlling the sludge discharge through said openings and mounted for axial reciprocation within the bowl, said piston being actuated to intermittent displacement partly by pressure of the treated liquid and partly by means of an actuating liquid influenced by centrifugal force, feeding means to conduct the actuating liquid to an annular groove in the bottom of the bowl and means to conduct the actuating liquid from the said annular groove to a space below said piston, said space being connected with a discharge arrangement for the actuating liquid, this discharge arrangement comprising a valve means and hydrostatic means for displacement of said valve means to an open position to permit the discharge of the actuating liquid and the simultaneous resulting movement of said piston to its complete open position for sludge discharge, means to permit the actuating liquid constantly to ooze out from the said space, automatic means controlled by the energy contained in the sludge for regulating the flow rate of actuating liquid conducted to the said annular groove, in relation to the rate of actuating liquid oozing out from the said space, to the effect of displacing said piston to a position for a partial opening of the sludge discharge openings in the bowl and a simultaneous partial sludge discharge, said automatic means holding the piston balanced in its partially open position without stopping the supply to the bowl of the material to be separated, said automatic means comprising a valve member placed in a feed pipe for conducting actuating liquid to said groove and space, the valve member being combined with an electro magnet for control of the valve member, means for regulating the intervals between the partial sludge discharges, the last mentioned means comprising a timer in connection with an electric contactor for intermittent breaking of an electric circuit giving current to the said magnet and a timer and an electric contactor for the closing of the circuit.
5. In the structure of a centrifugal separator as claimed in claim 4 in which the said electric contactor for the closing of the said circuit is actuated by electric tension impulses caused by the braking effect from sludge discharges on the driving electric motor.
6. In the structure of a centrifugal separator as claimed in claim 4 in which the said electric means for the closing of the said circuit is actuated by the sludge which is discharged from said peripheral sludge discharge openings, impinging a member connected to a contactor in the circuit of the magnet.
7. In the structure of a centrifugal separator as claimed in claim 4 in which said means to permit the actuating liquid constantly to ooze out of the space beneath the piston is associated with said discharge arrangement for the actuating liquid.
8. In the structure of a centrifugal separator as claimed in claim 1, in which said means to permit the actuating liquid constantly to ooze out of the space beneath the piston is associated with said discharge arrangement for the actuating liquid.
